OF LOS ANGELES, AND THEOFIEL CALLAERT, OF SAN FRANCISCO, CALIFORNIA.

APPARATUS FOR PRODUCING OIL GAS.

Application filed November 23, 1926. Serial No. 150,203.

The present invention relates to an apparatus for the production of gas from oil.

The principal object of the present invention is in the design and construction of

5 a gas generator wherein multiple streams of oil for generation are delivered into an apparatus in substantially different zones or chambers, the heat or combustion from one stream heating the wall against which the other streams project, insuring the proper temperature for its cracking. Another object is the provision of a suitable injector for the oil streams, whereby combustion in the presence of steam and air is assured. A 15 further object is the particular construction of the generator interior, whereby the maximum efficiency in an apparatus for this purpose is assured, and the gases generated by the cracking of the oil projected against the heated wall are intermixed with the gases of combustion and are conveyed from the generator for purification and further treatment in the well known practise of gas manufacture.

20 With the above and other objects in view, the invention consists broadly in the production of water and oil gas and oil from shale by what may be termed a down draft combustion process.

25 In the drawings disclosing the preferred embodiment of apparatus for carrying out the present invention—

Fig. 1 is a vertical sectional view of the oil gas generator.

30 Fig. 2 is a transverse sectional view on line 2—2 of Fig. 1.

Fig. 3 is a view in enlarged detail vertical section of the oil gas and air injector discharging into the dome of the oil gas generator.

Our present invention consists of an oil gas generator comprising a metallic or other casing 44, refractorily lined at 45, the two being insulated by a lining 44'. The gen-

45 erator is provided with the conventional cupola opening normally closed by a removable closure plate 47 through an opening in which is threaded at 48 a cylindrical shell 49 discharging axially into the generator

50 through a discharge opening 50. Air enters the shell through ports 51 and 52. Extending axially into the shell 49 and longitudinally adjustable therein is a means for supplying oil to be intermixed with steam to afford combustion and to maintain a high

temperature in the gas generating chamber 43, and the same comprises a steam injector nozzle 53 concentrically within which is disposed an oil discharge nozzle 54, the two nozzles discharging through the opening 50 60 in the shell 49. Oil is supplied to nozzle 54 through pipe 55, and steam is supplied to nozzle 53 through pipe 53' leading from a boiler or steam generator 56.

The shell 49 discharges downwardly 65 through an opening in the apex of a frusto-conical chamber 57 disposed concentrically within the gas generating chamber 43. The wall of the chamber is constructed preferably of refractory units 58 laid in successive 70 circumferential series with adjacent ends of certain of the units lying in spaced relation affording combustion outlets 59. The area of the outlets 59 increase as the successive series approach the checker hearth. The 75 frusto-conical chamber rises from a conventional brick checker hearth 60 downwardly through which extend passages 61 connected with oil gas collecting chambers 62 in the base of the generator, and from 80 which chambers leads a pipe or conduit 63 for connecting with the generator and boiler 56 for conducting oil gas from the gas generating chamber 43, the gas passing through the boiler 56 and discharging therefrom 85 through pipe, not shown, into a purifier, not illustrated. Against the units 58 forming the wall of chamber 57 is directed an atomized mixture of oil and steam discharging radially into the gas generating chamber 90 through the atomizers 64, which are similar in construction and arrangement as are the nozzles 53 and 54, illustrated in Fig. 3 of the drawings. The oil nozzles of the atomizers are supplied from a common feed 95 55' branching from pipe 55 and steam is supplied to the steam nozzle of each generator through a branch pipe 56' extended from the pipe 53'.

The atomized stream of oil, steam and air 100 discharging from the opening 50 into the apex of the frusto-conical chamber 57 strikes the upper surface of the checker hearth 60 and is ignited by the temperature thereof and the extreme heat thereof maintains its surface at a high temperature, and also maintains the units 58 in an extremely highly heated condition. The gases of combustion pass from the chamber 57 through outlets 105 59 and intermix with the gases within the 110

gas generating chamber 43 which are produced by cracking the atomized streams of oil and steam discharged on to the outer surface of the wall of the chamber 57 by the 5 battery of atomizers 64. The gases generated by the cracking and the gases of combustion passing from chamber 57 are drawn downwardly through the checker hearth 60, and the temperature thereof is maintained 10 sufficiently high thereby to ensure the production of oil gas. These gases pass through openings 61, through pipe 63, and steam generator 56, wherein the same are cooled, the heat absorbed therefrom generating steam 15 which is supplied to the members 53' and 56.

We claim:

An oil gas producing apparatus, comprising an oil gas generating chamber provided with a checkered hearth, a wall of refractory 20 material rising from said hearth concentri-

cally within said generator dividing its interior into a plurality of concentrically disposed chambers, said wall provided near its base with a plurality of apertures affording connecting passages between said chambers, 25 means for discharging a combustible mixture of oil, air and steam axially in a downward direction into said inner chamber and toward said checkered hearth, means for discharging a jet stream of oil and steam 30 against the outer surface of said refractory wall above said apertures, and means for withdrawing the resultant gases from said chambers through said checkered hearth.

In testimony whereof we have signed our 35 names to this specification.

AUGUST SCHILLING.
